CYLINDER CONSTRUCTION

Taito E. Huhtala, South Lyon, Mich., assignor to
 Vickers Incorporated, Detroit, Mich., a corpora-
 ration of Michigan

Application January 18, 1946, Serial No. 641,961

7 Claims. (Cl. 309—2)

1

This invention relates to power transmissions, particularly to those of the type comprising two or more fluid pressure energy translating devices, one of which may function as a pump and another as a fluid motor.

The invention is concerned generally with fluid motors of the type comprising a hollow cylinder in which is reciprocably mounted a piston connected to which is a piston rod and provided with ports connected to opposite sides of the piston. In the past, it has been customary to cap the ends of the cylinder by connecting head members thereto in one of several ways, such as by welding, by threading a head member over the ends of the cylinder, or by providing an abutment member on the outside wall of the cylinder, against which a cap or head member is either threaded or locked.

The invention is more particularly concerned with cylinder and reciprocating piston fluid motors of the type having ports which alternately act as inlet and discharge ports located at one end of the motor.

It is an object of this invention to provide a novel method of capping the ends of a fluid motor of the above types by providing abutment members stationarily mounted within the cylinder, mounting closure members within the cylinder, and capping the ends of the cylinder by locking head members to the closure members in such a manner that the capping members are held in abutment against the cylinder, and the closure members against the internally mounted abutment members.

It is also an object of this invention to provide an improved motor of this type by mounting two sleeves concentrically to each other so as to form an annular passage between the sleeves which is connected to one side of a piston reciprocably mounted in the inner sleeve and connecting one port to the opposite side of the piston and another port to the annular passage.

It is also an object of this invention to provide a motor of this type by concentrically mounting two hollow sleeves open at both ends in end caps containing stepped bores extending completely through the cap, closing said bores and cylinders at both ends thereof by a closure member mounted within the inner cylinder and locking the end cap to the closure member.

It is a further object to provide a motor of this type of improved and more rugged, compact, and reliable construction which is light in weight and capable of satisfactory operation over a long useful life.

2

Further objects and advantages of the present invention will be apparent from the following description, reference being had to the accompanying drawing wherein a preferred form of the present invention is clearly shown.

In the drawing:

Figure 1 is a sectional view of a preferred form of the invention taken along line 1—1 of Figure 5.

Figure 2 is an end view of the present invention.

Figure 3 is a sectional view taken along line 3—3 of Figure 2.

Figure 4 is a plan view of a housing containing control mechanisms shown in Figure 5.

Figure 5 is a longitudinal sectional view of a preferred form of the present invention taken along line 5—5 of Figure 2.

Referring now to Figure 5, there is illustrated, a fluid motor 10 comprising an inner sleeve 12 in which is reciprocably mounted a piston 14 to which is suitably connected a rod 16. There is also shown an outer sleeve 18 concentrically mounted together with inner sleeve 12 within stepped bores 20 of a right end cap 22 and a combined left end cap and control valve housing 24. The outer sleeve 18 is mounted on steps 26 of bores 20 with the extreme ends abutting shoulders 28, and inner sleeve 12 is mounted on steps 30 of said bore with the extreme ends of said sleeve abutting shoulders 32 also formed within bores 20 of the end caps 22 and 24. Inner sleeve 12 is provided with interior grooves 34 located near each end of the sleeve in which are placed snap rings 36 which abut against shoulders 38 of closure members 40 mounted within sleeve 12 at each end thereof and which have threaded portions 42 extending from the sleeve 12 through the bores 20 of end caps 22 and 24.

A bolt 44 threaded into end cap 22 and extending through sleeve 12 into the right end of closure member 40, prevents rotational movement of end cap 22 relative to sleeve 12. Mounting flanges 46 mounted on extended portions 42 of closure members 40, are suitably bolted to end caps 22 and 24. Lock nuts 48 are threaded over extended portion 42 of right end closure member 40 locking the closure member 40 against the snap rings 36. A ring bolt 50 is threaded into right end closure member 40 and secured to the latter by means of a lock nut 52, said ring bolt being adaptable for anchoring the motor 10.

Piston rod 16 is shiftable through a sleeve 54 inserted in stepped bore 20 of end cap 24, a scraper ring 56 and a retainer cap 58 for said ring, connected to the extended portion 42 of left

end closure member 40. A lock nut 59— together with retainer cap 58, serve the same purpose for the left end assembly as lock nuts 48 perform for the right end assembly. A bolt 60 threaded into end cap 24 and extending into left end closure member 40, prevents rotational movement of end cap 24 relative to member 40.

A housing portion 61 of end cap 24 contains a motor port 62 which is connected to the left side of piston 14 by means of a passage 64 in said housing, which is connected to said motor port and to a recessed port 66 in the left end closure member 40, the recessed port 66 being in communication with stepped bore 20. Another motor port 68 (Figures 2 and 4) is connected to an annular passage 70 formed between the inner and outer sleeves 12 and 18 by means of a passage 72, which is connected to port 68 and to a passage 74, the latter passage intersecting bore 80 and also a groove 75 connected to annular passage 70. Annular passage 70 is connected to the right side of piston 14 by means of ports 76, located in the right end of sleeve 12 which are in communication with ports 78 in the right end closure member 40 which open to stepped bore 23 of said closure member.

The motor port 62 is connected to a longitudinal bore 80 of the housing portion of end cap 24, by means of a passage 81 which intersects passage 64. Motor port 68 is connected to bore 80 by means of passages 72 and 74. Mounted within bore 80 is a control valve member 82 normally biased to a closed position against a seat member 84 by means of pressure fluid exerted against the right side of member 82. Pressure fluid may enter the bore 80 by means of a pressure port 86 connected to the right end of said bore.

By connecting a source of pressure to the pressure port 86, the valve 82 will be shifted to the left, but by venting the pressure port 86, pressure fluid entering either motor ports 62 or 68 will be by-passed around the motor. When pressure port 86 is vented, pressure fluid entering motor port 62 will shift valve 82 rightwardly unseating the same to permit fluid to be by-passed through seat member 84 into passage 74, and from seat member 84 to passage 72 and through port 68. If pressure fluid is directed to motor port 68 and pressure port 86 is vented, pressure fluid will be by-passed through port 62 by means of passage 74, seat member 84, and passage 64.

Referring to Figure 3, duplicate relief valves 88 and 90 are mounted in stepped bores 92 and 94, respectively, in the housing portion of end cap 24 which are connected to passages 64 and 72, respectively, by means of passages 81 and 74, respectively, for the purpose of relieving excessive pressure fluid in either passage.

Motor 10 is particularly adaptable to aircraft automatic pilot systems wherein a four-way control valve, not shown, may be connected to a source of pressure and a reservoir and also connected to the cylinder ports 62 and 68 of motor 10. Thus, with a source of pressure in the system, connected to pressure port 86 so as to shift control valve 82 to the left, the control valve, not shown, would direct pressure fluid to either cylinder port 62 or 68, and discharging fluid from either of said ports to the reservoir so as to control the shifting of piston 14 to the right or left. By providing venting means for port 86 of motor 10, as aforementioned, control valve 80 is shifted rightwardly by pressure fluid in either passage 81 or passage 74 so as to by-pass motor 10, and inactivate the same.

It should be noted, however, that, where a simple cylinder and reciprocal piston motor of the type having two ports located at one end of the motor is desired, it is a simple matter to provide a housing for the left end of motor 10 containing cylinder ports directly connected to the left end of piston 14, and to the right end thereof by connecting one of said ports to the annular passage 70.

It should also be noted that, by mounting closure members 40 within the inner sleeve 12, and providing the internal snap rings 38 as an abutment therefor, the inner and outer sleeves 12 and 18 may be simply mounted in the end caps 22 and 24, and the total assembly of the sleeves, closure members, and end cap may be easily secured in assembled position by the use of lock nuts threaded on the extended portions 42 of closure members 40.

While the form of embodiment of the invention as herein disclosed constitutes a preferred form, it is to be understood that other forms might be adopted, all coming within the scope of the claims which follow.

What is claimed is as follows:

1. A fluid motor comprising a hollow cylinder, a piston reciprocably mounted within the cylinder, spaced apart ring members stationarily mounted within the cylinder, a pair of closure members mounted within the cylinder at each end thereof and abutting the ring members, said closure members each having a portion extending from the cylinder, a pair of end caps having stepped bores mounted on the extended portions of the closure members and within which the cylinder is mounted, and locking means connected to the extended portions holding the closure members in abutment against the ring members.

2. A fluid motor comprising a hollow cylinder, a piston connected to which is a piston rod reciprocably mounted within the cylinder, spaced apart ring members stationarily mounted within the cylinder, a pair of closure members, one of which contains a bore through which the piston rod is shiftable, mounted within the cylinder at each end thereof and abutting the ring members, said closure members each having a portion extending from the cylinder, a pair of end caps having stepped bores mounted on the extended portions of the closure members and within which the cylinder is mounted, and locking means connected to the extended portions holding the closure members in abutment against the ring members.

3. A fluid motor comprising a cylinder having a longitudinal bore open at both ends, a piston connected to which is a piston rod reciprocably mounted in the bore, a pair of ring members stationarily mounted within the bore near each end thereof, a pair of closure members, one of which contains a bore through which the piston rod is shiftable mounted, within the cylinder bore at each end thereof, said closure members each having a shoulder adapted to abut against the snap rings and each having a portion extending from the bore, a pair of end caps having stepped bores extending completely through the same mountable on the extended portions of the closure members and within which the cylinder is mounted, said bores containing shoulders against which the extreme ends of the cylinder are adapted to abut, and locking means connected to the extended portions holding the closure members in

abutment against the ring members and the end caps against the extreme ends of the cylinder.

4. A fluid motor comprising a first cylinder having a longitudinal bore extending completely through the same, a second cylinder having a bore extending completely through the same, a pair of closure members mounted in each end of the first cylinder bore, said closure members each having a portion extending from the cylinder bore, a pair of ring members stationarily mounted within the first cylinder bore and against which the closure members are adapted to abut, a pair of end caps having stepped bores and mounted on the extended portions of the closure members, said first cylinder being mounted on steps and said second cylinder being mounted on other steps within the stepped bores of the ends of the end caps, an annular passage formed between the cylinders, means connected to the extended portions of the closure members holding the cylinders within the end caps and the first cylinder in abutment against the ring members, means forming a first and second port in one end cap, means connecting the first port to one end of the first cylinder bore, means connecting the annular passage to the opposite end of the first cylinder bore, and means connecting the second port to the annular passage.

5. A fluid motor comprising a first hollow cylinder, a second hollow cylinder, a pair of spaced apart ring members stationarily mounted within the first cylinder, a pair of closure members mounted within the first cylinder at each end thereof abutting the ring members, a pair of end caps having stepped bores abutting the extreme ends of the cylinders, said cylinders being mounted on steps of said bores, with the first cylinder within the second cylinder, means locking the end caps to the closure members to securely hold said caps in abutment against the ends of the cylinders and the closure members in abutment against the ring members, means forming a port in communication with one end of the first cylinder, and means forming another port in communication with the opposite end of the first cylinder.

6. A fluid motor comprising a first hollow cylinder, a second hollow cylinder, a pair of spaced apart ring members stationarily mounted within

the first cylinder, a pair of closure members mounted within the first cylinder at each end thereof abutting the ring members, a pair of end caps having stepped bores abutting the extreme ends of the cylinders, said cylinders being mounted on steps of said bores, with the first cylinder within the second cylinder to form an annular passage between the cylinders, means locking the end caps to the closure members to securely hold said caps in abutment against the ends of the cylinders and the closure members in abutment against the ring members, means forming a port in communication with one end of the first cylinder, means forming another port in communication with the annular passage, and means connecting the annular passage to the opposite end of the first cylinder.

7. A fluid motor comprising a first hollow cylinder, a second hollow cylinder, a pair of spaced apart ring members stationarily mounted within the first cylinder, a pair of closure members mounted within the first cylinder at each end thereof abutting the ring members, a pair of end caps having stepped bores abutting the extreme ends of the cylinders, said cylinders being mounted on steps of said bores, with the first cylinder within the second cylinder to form an annular passage between the cylinders, means locking the end caps to the closure members to securely hold said caps in abutment against the ends of the cylinders and the closure members in abutment against the ring members, means forming a port located near one end of the motor in communication with one end of the first cylinder, means forming another port near the same end of the motor in communication with the annular passage, and means connecting the annular passage to the opposite end of the first cylinder.
